UNITED STATES PATENT OFFICE.

CLEMENT C. SMITH, OF WHEELING, WEST VIRGINIA.

CAR-DUMPING PLATFORM.

1,380,745.

Specification of Letters Patent.

Patented June 7, 1921.

Application filed August 26, 1919. Serial No. 319,945.

To all whom it may concern:

Be it known that I, CLEMENT C. SMITH, a citizen of the United States of America, and resident of Wheeling, county of Ohio, and 5 State of West Virginia, have invented certain new and useful Improvements in Car-Dumping Platforms, of which the following is a specification.

This invention relates broadly to car 10 dumping apparatus, and more particularly to an automatic dump-platform for mine cars and the like.

The primary object of the invention is to provide a simple and comparatively inexpensive load-dumping device for mine cars and other cars from which the load is discharged through an end thereof by gravity or by the impetus produced when the car assumes an inclined position.

20 A further object is to provide a car arresting and dumping platform which is automatically actuated to assume its inclined car-dumping position when the forward movement of the latter is arrested.

25 A still further object is to provide a dumping platform of the character mentioned which is adapted to automatically resume its normal horizontal position following the dumping operation, and which is provided 30 with means whereby adjustment may be made to suit various cars and conditions of car loading so that not only is the complete emptying of the car insured, but also the return of the platform and car to normal 35 position following unloading of the latter.

Another object within the contemplation 40 of this invention is to provide a "through-dump," which may be defined as a car-dumping device located intermediate the ends of a trackway and so arranged that it may either be operatively disposed for arresting the forward travel of cars thereover and for effecting the dumping of cars so arrested, or rendered inoperative for dumping cars by 45 disposing it in position wherein cars are permitted to unobstructedly travel thereover to the portion of the trackway located in advance thereof.

With these and other important objects in 50 view, the invention resides in the features of construction, arrangement of parts and combinations of elements which will hereinafter be exemplified, reference being had to the accompanying drawings, in which—

55 Figure 1 is a side elevation of the invention with portions broken away;

Fig. 2 is a section taken substantially on the line 2—2, Fig. 1;

Fig. 3 is a top plan view;

Fig. 4 is an enlarged top plan view of a means whereby adjustment is effected for insuring the return of the car and platform to normal position following the dumping operation; and—

Fig. 5 is a partial longitudinal section of the same.

Referring to said drawings, in which like designating characters refer to like parts throughout the several views—

1 indicates the upright supporting timbers of a tipple structure which may be of any appropriate construction, but which, as herein shown for illustrative purposes, comprises longitudinally disposed I-beams 2 resting upon transverse supporting members 75 3. Leading onto the tipple and mounted upon suitable timbers, as 4, are track rails 5 with the ends of which register the rear ends of aligned rails 6 that are mounted upon the dumping platform which constitutes the 80 main or essential feature of the present invention.

Said dumping platform comprises a pair of parallel longitudinally extending rockers 7 which are herein shown as resting upon channel members 8 that are seated upon the top surface of the I-beams 2. The under sides or bottom surfaces of said rockers are of sled-runner form, each having a plain straight portion and an upwardly and forwardly curved portion or surface, the latter located adjacent to the front end of the rocker and constituting a surface 7^a upon which the platform may rock or roll forward to the inclined position indicated in 95 dotted lines in Fig. 1. Said rockers may be of I-beam form in cross-section, as shown, or may be of other cross section and may be composed of any preferred material.

Superposed upon said rockers 7 are the 100 platform track-rails 6 hereinbefore referred to, the same extending forward a suitable distance in advance of the front ends of said rockers and carrying at or adjacent to their front ends chocks, as 9 and 10, adapted to 105 be engaged by the front wheels 11 of a car 12 for arresting forward movement of the latter when it has assumed a position on the platform appropriate for dumping. As herein shown, said chocks 9 and 10 are constituted by bending the front ends of said rails 6 upward into suitable form. It will 110

be understood, however, that the chocks need not form integral parts of said rails 6.

A transverse tie-rod 13, which may be one of a plurality employed for connecting and maintaining in spaced relation the two opposite rockers 7, is disposed adjacent to the front ends of said rockers in an appropriate position. Pivoted upon the opposite ends of said tie-rod 13, or to suitably located 10 pivot pins carried by said rocker, are the upper ends of downwardly and forwardly inclined links 14 which have their opposite ends pivotally mounted at suitable points on the tipple structure, as upon the ends of a 15 suitably located transverse rod 15 carried by the I-beams 2.

Theoretically, the arrangement of the various parts of the structure above described is such that the center of gravity of a car, 20 either loaded or unloaded, which stands at rest on the platform in the farthest advanced position permitted by the wheel chocks, is located in a vertical transverse plane intersecting the rockers 7 at the points 25 where the tangents constituted by the plain straight under surfaces of said rockers meet the curved surfaces 7^a of the latter. Also, theoretically, the curve described by the surface 7^a is struck with a radius having a 30 length equal to the vertical distance from the plane of the bottoms or under sides of the rockers 7 to the center of gravity of the empty car and platform. Consequently, when the car is at rest in the position indicated in full lines in Fig. 1, an approximate 35 balance is maintained—that is, the equilibrium of the platform and the car mounted thereon is of such unstable character that a slight or practically negligible force will 40 overbalance the platform with the loaded car thereon, the rockers 7 being caused to roll forward on their curved surfaces 7^a. This results from the circumstance that the slight force above referred to advances the center 45 of gravity of the load in front of that of the car and platform. This rolling forward of the platform, as aforesaid, causes the car to assume the dotted line position thereof indicated in Fig. 1, in which the inclination is 50 such that the load will slide by gravity from the car.

As ordinarily equipped, mine cars are provided with end-gates secured in place by means of latch mechanism which is actuated 55 to automatically release the gate as the car assumes its inclined dumping position, allowing the gate to swing open for releasing the load. Immediately when the gate opens, some of the forward part of the load will 60 slide from the car and the center of gravity of the load will consequently be shifted toward the rear of the car, producing a tendency in the car and the car-supporting platform to swing or fall back to their normal horizontal position. Obviously, this

tendency may be counteracted by so arranging the latch mechanism that it will not release the end-gate until the forward inclining motion of the car has attained a momentum sufficiently great to overcome the effect 70 of the aforesaid shifting of the center of gravity of the load.

As hereinbefore indicated, when the length of the radius of the curved surfaces 7^a of the rockers is equal to the distance from the 75 plane of the bottom surfaces of the rockers to that of a parallel plane passed through the center of gravity of the empty car and platform, the car will, theoretically considered, remain in any position to which it is moved 80 between the points indicated in full lines and in dotted lines in Fig. 1. It will therefore be understood that when the loaded car is caused to engage the chocks with considerable force, as ordinarily, the momentum will 85 be sufficient to carry the car and platform to dumping position at a speed which will result in the load being promptly dislodged or discharged from the car. Incidentally, it may here be pointed out that if the position of the wheel chocks be slightly advanced 90 so that when the wheels engage the latter the center of gravity of the load is slightly in advance of a vertical transverse plane intersecting the points at which the tangents constituted by the bottoms of the rockers 7 meet the curved surfaces 7^a of the latter, the speed 95 at which the car and platform assume inclined dumping position will be greatly increased.

If the curved surfaces 7^a of the rockers be produced on a radius greater than the distance between the bottoms of the rockers and the center of gravity of the empty car and platform—that is, if the length of the radius 100 be increased toward the center of gravity of the loaded car—the tendency will be for the platform and car to roll back to normal position following dumping. Since the height 105 of the centers of gravity of different empty cars will obviously vary, as also the location of the centers of gravity of variously loaded cars, and it is consequently impossible that the curved surfaces 7^a shall be so produced 110 that the dumping and return movements of the cars shall invariably be effected automatically, it becomes important that means of adjustment be afforded whereby the platform may be adjusted to suit various cars and conditions of loading. Instead of 115 changing the curvature of the curved surfaces of the rockers to suit the radial distance of the center of gravity, it is preferred that means be employed involving the provision of a device whereby the grade or inclination of the surface upon which the rockers roll may be varied. For purposes of illustration of such means I have herein shown the front end portions 8^a of the channel members 8, upon which rock or roll the surfaces 120

130

7^a of the rockers 7, as adapted to be inclined more or less with respect to the plane of the surface upon which the bottoms of said rockers rest, thus changing the grade upon which 5 said rockers travel. A wedge 16 having its edge introduced under each of said portions 8^a is adjustable for changing the inclination of the latter. Said wedge may be secured in adjusted position in any suitable manner, as 10 by means of one or more bolts 17 carried by the underlying I-beams 2 and extending through a longitudinal slot or slots 18 provided therefor in the wedge. It is evident, however, that various other simple means 15 may be employed for adjusting the inclination of said portions 8^a.

The extent of the forward tipping movement of the car may be limited by the provision of a suitable bumper, as 19, at a suitable 20 point adjacent to the upper end of the chute 20 upon which the load is deposited or dumped, said bumper being adapted to have a suitable part, as the under side of the front end of the car, seat thereon, as indicated in dotted lines in Fig. 1.

The links 14 are designed as a means of maintaining the rockers against longitudinal sliding movement upon the surfaces upon which they rock or roll as aforesaid. It is 30 evident, however, that said links constitute but one of various equivalent means which might be employed for this purpose.

It is frequently desirable that the dumping platform be located in an intermediate 35 position in a trackway so that cars may travel thereover, as to and from more advanced dumping positions on the tipple. To adapt the platform for permitting of such travel thereover—that is, to adapt it for use 40 as a "through dump"—the platform rails 6 are mounted upon a suitable frame, as that constituted by the transverse bars 21, rather than directly upon the rockers 7, and said bars 21 are in turn mounted upon said 45 rockers so as to be laterally shiftable for carrying said rails 6 into and out of register with the track rails 5. Also mounted upon said bars 21 parallel to and at a suitably spaced distance from said platform rails 50 6 are straight rail sections 22 which in the shifted position of said bars register at their rear ends with said track rails 5 and at their front ends with rail sections 23 located at the adjacent end of an advanced portion of 55 the trackway. Said rail sections 23 are arranged to be movable to a position wherein they will in no way obstruct the movement of the car to dumping position, as to the approximately vertical position shown in 60 dotted lines in Fig. 1, when the platform described is utilized for dumping purposes. Normally, however, said rail sections have their rear ends resting upon suitable seats, as 24, mounted upon the I-beams 2, as 65 shown. The front ends of said sections have

pivotal connection through straps 25 or other equivalent means with the adjacent ends of the rails 26 of a permanently seated portion of the trackway.

As is obvious, when it is desired that cars 70 pass unobstructedly over the platform to said rails 26, the frame with the rail sections 6 and 22 mounted thereon is bodily shifted to the position indicated in dotted lines in Figs. 2 and 3. In said position, the front 75 ends of the rail sections 22 rest upon the adjacent ends of the seats 24, preventing tipping movement of the platform. Any preferred mechanism for effecting the lateral shifting of the frame and superposed 80 rail sections may be employed.

To permit of the unobstructed travel of cars over the straight rail sections 22, the chock 10 of the rail section 6 which occupies a position between said rail sections 22 is 85 made of relatively short length so that it will not be engaged by the axles of cars passing thereover, as is most clearly indicated in dotted lines in Fig. 2. As is manifest, since the opposite rail section 6 is located laterally of the path of cars traveling over said rail sections 22, the chock 9 thereof may be of any desired height.

It will be evident from the foregoing description that the invention is susceptible of 90 considerable variation in the forms of some of its parts and that various changes and modifications may be resorted to without departing from the general scope and spirit of the invention as defined in the appended 95 100 claims.

What is claimed is—

1. The combination with a tipple structure having track rails leading thereto, of a dumping platform comprising a pair of opposite longitudinally disposed rockers having approximately sled-runner form, unyielding supports for said rockers, rail sections superimposed on and wholly supported by said rockers with their rear ends in 110 register with said track rails, wheel chocks carried adjacent to the front ends of said rail sections, and means for preventing longitudinal movement of said rockers on said supports.

2. The combination with a tipple structure having track rails leading thereto, of a dumping platform comprising a pair of opposite longitudinally disposed rockers having approximately sled-runner form, unyielding supports for said rockers, rail sections superimposed on and wholly supported by said rockers with their rear ends in 115 register with said track rails, wheel chocks carried adjacent to the front ends of said rail sections, and adjustable means for inclining the surfaces upon which the curved surfaces of said rockers rock when the latter are tipped forward.

3. The combination with a tipple struc- 130

ture having track rails leading thereto, of a dumping platform comprising unyielding supports, a pair of opposite longitudinally disposed rockers mounted upon said supports, said rockers having the under surfaces of their front ends curved upwardly and forwardly upon a suitable radius, rail sections superposed over and wholly supported by said rockers with their rear ends 10 in register with said track rails, suitably located means for arresting the advance of a car which mounts said rail section, and adjustable means for varying the speed at which said rockers rock forward on their 15 curved surfaces for carrying a car to dumping position.

4. The combination with a tipple structure having track rails leading thereto, of a dumping platform comprising a pair of opposite longitudinally disposed rockers of approximately sled-runner form, rail sections superimposed on and sustaining the entire weight of said rockers, said rail sections having their rear ends in register with said 20 track rails, wheel chocks carried adjacent to the front ends of said rail sections for arresting the advance of a car which mounts said rail sections, said rockers being adapted to be automatically actuated by a car engaging 25 said chocks to rock forward on the curved surfaces thereof for carrying the car to dumping position, and means for varying the speed at which the rockers operate.

5. The combination with a tipple structure having track rails leading thereto, of a dumping platform comprising a pair of opposite longitudinally disposed rockers having the under surfaces of their front ends curved upwardly and forwardly, rail sections superimposed on said rockers with their rear ends in register with said track rails, wheel chocks carried adjacent to the front ends of said rail sections for arresting 35 the advance of a car which mounts said rail sections, said rockers being adapted to be automatically actuated by a car engaging said chocks to roll forward on the curved surfaces thereof for carrying the car to dumping position, said curved surfaces being produced on a radius having a length at least equal to the vertical distance from the plane of the bottoms of said rockers to that of the center of gravity of the empty car and platform.

6. The combination with a tipple structure having track rails leading thereto, of a dumping platform comprising a pair of opposite longitudinally disposed rockers having their under surfaces of approximately 40 sled-runner form, rail sections superimposed on and wholly supported by said rockers, said rail sections having their rear ends in register with said track rails, wheel chocks carried adjacent to the front ends of said rail

sections for arresting the advance of a car 65 which mounts said rail sections, said rockers being adapted to be automatically actuated by a car engaging said chocks to roll forward on the curved surfaces thereof for carrying the car to dumping position, said 70 curved surfaces being produced on a radius having a length at least equal to the vertical distance from the plane of the bottoms of said rockers to that of the center of gravity of the empty car and platform, unyielding 75 supports upon which said rockers rest, said supports having their upper surfaces disposed in an approximately horizontal plane, and adjustable means for inclining the portions of said surfaces upon which the curved 80 surfaces of said rockers rock or roll to cause the automatic return of the car and platform to normal position following the dumping operation.

7. The combination with a tipple structure having track rails leading thereto, of a car dumping platform comprising approximately horizontal supports, a pair of opposite longitudinally disposed rockers having the plane under surfaces resting upon said 90 supports and having the under surfaces of their front ends upwardly and forwardly inclined, inclinable members disposed in underlying relation to said inclined portions of said rockers and adapted to have said portions mount thereon when said rockers are rolled forward, means for adjusting the inclination of said members, and rail sections superimposed on said rockers and having their rear ends in register with said track 95 rails, the front ends of said rail sections being curved upward to form wheel chocks, said platform being adapted to automatically rock forward to car-dumping position when a car has mounted said platform and 100 to return to normal position following the dumping operation.

8. A through-dump for tipples consisting of a trackway having interposed therein a dumping platform; said platform comprising a pair of opposite longitudinally disposed rockers having their under surfaces of approximately sled-runner form, a frame superposed upon and laterally slidable with respect to said rockers, a pair of parallel 110 straight rail sections carried by said frame and adapted in one position of the latter to complement the portions of the trackway located forward and rearward of the platform whereby a through track is provided, and a pair of rail sections carried by said frame parallel to said straight rail sections and having wheel chocks associated with their front ends; means for shifting said frame laterally to carry either of said pairs 115 of rail sections into register with the platform-approaching portion of the trackway, the curved portions of the under surfaces of

- so disposed with respect to the location of 65
the center of gravity of a loaded car which
is disposed upon said rail sections against
said chocks that said rockers are automatic-
ally actuated to rock forward on said sup-
ports to a position in which the load is 70
dumped from said car.
12. A dumping platform for cars comprising,
in combination with supports having 75
plane surfaces, of a pair of parallel rockers
seated upon said surfaces, said rockers having
rail sections superposed thereon for receiving
cars to be dumped, suitably located wheel
chocks associated with said rail section, said
rockers having the under surface portions of
the front ends thereof upwardly and for-
wardly curved and so disposed with respect 80
to the location of the center of gravity of a
loaded car which rests upon said rail sections
against said chocks that said rockers are
automatically actuated to rock forward on 85
said supports to a position in which the load
is dumped from said car, and also so dis-
posed that the weight of the empty car act-
ing through its changed center of gravity
automatically actuates the platform to re- 90
turn to normal position following the dump-
ing operation.
13. A dumping platform for cars comprising,
in combination with supports, a pair of 95
parallel rockers mounted on said supports,
said rockers having rail sections superposed
thereon for receiving cars to be dumped,
suitably located wheel chocks associated with
said rail sections, said rockers having the
front end portions thereof upwardly and 100
forwardly curved and so disposed with re-
spect to the location of the center of gravity
of a loaded car which is disposed upon said
rail sections against said chocks that said
rockers are automatically actuated to rock 105
forward on said supports to a position in
which the load is dumped from said car, and
adjustable means for inclining the planes of
the supports upon which said platform rocks
forward as aforesaid for causing the latter 110
to rock rearward to normal position follow-
ing the dumping operation.
14. A dumping platform for cars comprising,
in combination with supports provided 115
with upper surfaces disposed in an approxi-
mately horizontal plane, a pair of parallel
rockers seated upon said upper surfaces, said
rockers having rail sections superposed
thereon for receiving cars to be dumped,
suitably located wheel chocks associated with 120
said rail sections, said rockers having the
under surfaces of the front end portions
thereof upwardly and forwardly curved and
so disposed with respect to the location of
the center of gravity of a loaded car which 125
is disposed on said rail sections against said
chocks that said rockers are automatically
actuated to roll forward on said supports to
- said rockers having such curvature that
when the wheels of a car assume seated rela-
tion to said chocks, the platform will roll on
said curved portions, carrying the car to an
inclined position in which the load is
dumped therefrom, and means for support-
ing said platform against forward tipping
when the straight rail sections are in register
with the adjacent portions of the trackway.
- 10 9. A through-dump for tipplers consisting
of a trackway having interposed therein a
dumping platform; said platform comprising
a pair of opposite longitudinally dis-
posed rockers having their under surfaces of
approximately sled-runner form, a frame
superposed upon and laterally shiftable with
respect to said rockers; a pair of parallel rail
sections carried by said frame and adapted
in one position of the latter to register with
the platform-approaching portion of the
trackway, said rail sections having wheel
chocks located adjacent to their front ends
whereby the travel of a car mounting said
sections is arrested; said platform being
actuated by gravity assisted by the impetus
of the suddenly arrested car to rock forward
on said rockers for tipping said car to load-
dumping position; a pair of straight rail
sections carried by said frame laterally of
the first mentioned rail sections and adapted
in another position of said frame to comple-
ment the portions of the trackway located
forward and rearward of the platform
whereby a through track is provided, means
for shifting said track laterally to carry
either of said pairs of rail sections into op-
erative position, and means whereby the
platform is stabilized when the pair of
straight rail sections occupies operative posi-
tion.
- 10 10. A dumping platform for cars comprising
a pair of parallel rockers having rail
sections superposed thereon for receiving
cars to be dumped, suitably located wheel
chocks associated with said rail sections, said
rockers having the under surfaces thereof of
approximately sled-runner form so that,
when a loaded car advances upon said sec-
tions into engagement with said chocks, the
rockers are automatically tipped forward to
a position in which the load is dumped from
said car and, following such dumping, are
automatically returned to normal position
through shifting of the location of the center
of gravity.
11. A dumping platform for cars comprising
a pair of parallel rockers having rail
sections superposed thereon for receiving
cars to be dumped, supports having plane
surfaces upon which said rockers normally
rest, suitably located wheel chocks associated
with said rail sections, said rockers having
the under surface portions of the front ends
thereof upwardly and forwardly curved and

a position in which the load is dumped from said car, and adjustable means for inclining the planes of the portions of said supports upon which said platform rocks forward as 5 aforesaid to suit various cars and various conditions of loading so that, due to the shifting of the center of gravity produced by the dumping of the load, the empty car and

platform will automatically return to normal position.

In testimony whereof, I affix my signature 10 in presence of two subscribing witnesses.

CLEMENT C. SMITH.
